UNITED STATES PATENT OFFICE.

FREDERICK W. WERNER AND HARRY C. KENDALL, OF DENVER, COLORADO; SAID
WERNER ASSIGNOR TO SAID KENDALL.

RAILWAY TRANSFER-TICKET.

1,294,735.

Specification of Letters Patent. Patented Feb. 18, 1919.

Application filed June 21, 1917. Serial No. 176,093.

To all whom it may concern:

Be it known that we, FREDERICK W. WERNER and HARRY C. KENDALL, citizens of the United States, residing at Denver, in the county of Denver and State of Colorado, have invented certain new and useful Improvements in Railway Transfer-Tickets, of which the following is a specification.

This invention relates to railroad tickets 10 and more particularly to improvements in tickets of the type used on street railways to entitle passengers to transportation over lines connecting with that on which the tickets were issued by the conductor upon receipt of the required fares.

These tickets, commonly known as transfers or transfer-tickets, bear upon their face in addition to the necessary printed matter relating to the line or lines upon which they 20 are valid, the hours of issuance or expiration and other information relative to their use and value, the period of time during which they may be tendered in lieu of a cash-fare on a designated line or lines.

25 It has heretofore been customary to designate the day and date of issuance or expiration upon the face of the tickets by printing a row of numbers to represent the days of the month, and a list giving the names 30 of the months in their convenient order. The conductor before issuing the transfer, punches the month and day upon which the transaction takes place, and in some cases also punches a separate inscription which 35 designates by the letters A. M. or P. M. the time of the day with respect to the meridian.

Transfer tickets of this description are sometimes modified by printing thereon the number of the particular day with or without 40 the name of the particular month during which they are used.

Principal among the objections to the use of transfer-tickets of the above described character are—

45 First. The waste of time and liability to error connected with punching the designated day and month, even though this is done in the office of the railway company, as is often resorted to to save the time of 50 the conductors and thereby expedite travel.

Second. The waste of unused material which naturally occurs when a quantity of tickets are printed or otherwise designated for any particular period without the pos-

sibility of foretelling the number to be issued during said period. 55

Third. The impossibility of effectively guarding against fraudulent use of tickets by either passengers or employees of the 60 railway, and

Fourth. The time wasted and errors unwillingly made by conductors to whom the tickets are tendered, in deciphering, by reading the printed names and numbers or other designations, the date and period of the 65 day on and during which the transfer was issued.

It is the object of the present invention to eliminate any and all of the above enumerated objectionable features, by providing a transfer which in unmistakable symbols designates a predetermined period during which it may be used, without the use of numbers or words which inform the passengers of the date or period of its validity. 70 75 and without the necessity of indicating the same by punching or other mutilation of the tickets.

It is another object of the invention to positively prevent the waste of unused material, experienced in any one of the systems above referred to, by designating the period of validity of the tickets in such a manner that they may be used unaltered on different days without sacrificing any of 80 the characteristics which render them proof against fraudulent use, and still another object of the invention is to provide a transfer with matter limiting the period of its 85 validity, which is at a glance recognized by 90 the conductor, and thereby obviates the scrutiny required of the conductors in accepting transfers of the kind at present in common use.

The above and other objects, all of which 95 will fully appear in the course of the following description, we attain by placing upon the face of the transfer by printing, stamping, puncturing or any other suitable method, a symbol of arbitrary design to designate by characters or marks different from those ordinarily used for this purpose, the day of the month or any other predetermined period during which the tickets are accepted in payment of transportation. 100 105

The symbols on tickets to be issued during different consecutive periods, differ either in character or arrangement and they are not

divulged to the public or the employees of the railway company until the beginning of the period during which the tickets are to be used, thereby frustrating fraudulent use, 5 since no one with the exception of the official intrusted with the selection of the symbol for each particular period of time, knows what particular marks or combinations of marks are to be used on following days or 10 periods.

By making the symbol printed upon the face of the ticket large and bold in appearance, it may be recognized at a glance by conductors receiving the same, thereby preventing errors and saving much time especially on the so-called "pay as you enter" cars on which fares are collected from passengers as they enter the vehicle.

Inasmuch as under our improved system it 20 is possible to use the same symbol repeatedly without in any way deteriorating the value thereof as a safe and simple medium to prevent fraudulent use of the tickets upon which it is used, waste by the loss of unused 25 tickets bearing designations for their issuance on specified dates, is completely avoided and the arbitrary, periodically changed character of the symbols, renders punching or other methods of designation unnecessary. 30 Without desiring to be limited to the use of any particular system of symbols, we preferably use on each ticket a symbol composed of two or more characters or other marks which being interchangeable, may be 35 arranged to present a large number of combinations.

The symbol may be accompanied by characters designating the period of the day during which the tickets bearing them are valid, 40 or the symbols may themselves designate the periods by either different colors, shadings or other differentiating characteristics, it being understood that it is desirable to use the same symbol during an entire day 45 and distinguish the periods of the day before and after the meridian by any of the means above referred to.

In the accompanying drawings in the various views of which like parts are similarly designated,

Figures 1 and 2 show tickets according to our invention hereinbefore referred to, one being designed for use in the forenoon of the day designated by the symbol, and the 55 other during the afternoon of the same day, and

Fig. 3 shows a fragmentary face view of a ticket illustrating the use of a symbol different from those shown in the other 60 views.

Referring more specifically to the drawings, the reference character 2 designates a transfer ticket having printed upon its face a column 3 in which are arranged the hours 65 of the day and fractions thereof, which in

the use of the ticket are punched upon their issuance to designate the time of its expiration.

The ticket also has a space 4 giving the number of the route on which it is issued, 70 and below the same, a list 5 of lines upon which it is acceptable, the particular line upon which it may be used during the indicated period being designated by punching the space opposite its name. 75

The ticket furthermore bears upon its face the conditions under which it is acceptable by the purchaser, as shown at 6, its serial number as designated by the numeral 7, and such other matter as may be required to provide a transfer ticket which is adapted for use under different circumstances and conditions. 80

It will be observed that the ticket bears neither names nor numbers to designate in 85 the conventional manner the period during which it is valid. Instead of these usual designations, it bears in the space designated by the reference numeral 8, a symbol 9 preferably composed of an arbitrary combination of arbitrary marks which individually are non-significant (in the example shown in the drawings, the characters H and A) and which are printed in type sufficiently bold and large that they may be seen at a 90 glance and without scrutiny of the ticket. 95

The symbols on the ticket shown in Fig. 1 are printed in one color to indicate that the ticket may be used only during a certain period of the day, as for example the forenoon, and the symbol on the ticket shown in Fig. 2 has been printed in another, contrasting color to show its validity during the post meridian period of the same day. 100

In the use of transfer tickets made in accordance with our invention the conductors are apprised only at the time they commence their duties for the day, of the symbol to be used on the transfer tickets during that day, to distinguish them from transfers to be used during other days of the month or year. 105

When receiving transfer-tickets issued on other lines, the conductors can detect their validity at a glance. 115

The tickets are not punched or otherwise mutilated except at the time they are issued, and then only to indicate the hour of expiration and the line upon which they may be used so that at the end of the day the conductor can return the unused tickets to the office from which they were supplied, in a condition suitable for use on another day. 120

Fraudulent use of the tickets by either passengers or conductors is completely 125 avoided and the waste ordinarily caused by quantities of left-over tickets good only on a certain designated date, is eliminated.

It will furthermore be observed that the use of transfer tickets made in accordance 130

with our invention requires the provision of comparatively few different kinds, inasmuch as the use of a limited number of marks in combination of two or more, is sufficient to effectively guard against the fraudulent use of the tickets as often practised by unscrupulous passengers or dishonest employees.

In Fig. 3 of the drawings the symbol 9 10 consists of the pictorial representation of a flag as an example of the use of symbols other than those composed of combinations of characters as hereinbefore described.

It will be understood that while transfers 15 bearing a particular validating symbol of the character herein described are usually issued for only one day or any determinate part thereof, they may be effectively used during two or more consecutive days or any 20 other predetermined period of time.

Having thus described our invention what we claim and desire to secure by Letters-Patent is:

1. A transfer ticket for issuance to or 25 from public conveyances, comprising a slip which bears upon its face, matter constituting it a valid medium for the transference of passengers from one carline to another, and in nonseparable relation to said matter, 30 a distinctive symbol composed of one or more arbitrary characters, which signifies without other designation, a predetermined period of its validity.

2. A transfer-ticket for issuance to or 35 from public conveyances, comprising a slip which bears upon its face matter constituting it a valid medium for the transference of passengers from one carline to another, and in nonseparable relation to said matter, a 40 distinctive symbol composed of two or more arbitrary characters which, in combination, signify without other designation, a predetermined period of its validity.

3. A transfer-ticket for issuance to or 45 from public conveyances, comprising a slip which bears upon its face, matter constituting it a valid medium for the transference of passengers from one carline to another,

and in nonseparable relation to said matter, a distinctive symbol composed of one or more 50 arbitrary characters, which signifies without other designation a determinate day of a determinate month.

4. A transfer-ticket for issuance to or from public conveyances, comprising a slip 55 which bears upon its face, matter constituting it a valid medium for the transference of passengers from one carline to another, and in nonseparable relation to said matter, a distinctive symbol composed of one or 60 more arbitrary characters, which signifies without other designation, a determinate part of a determinate day of a determinate month.

5. A transfer-ticket for issuance to or 65 from public conveyances, comprising a slip which bears upon its face matter constituting it a valid medium for the transference of passengers from one carline to another, and in nonseparable relation to said matter, 70 a distinctive symbol composed of one or more arbitrary characters, which signifies without other designation, a determinate day of a determinate month, and which has an additional characteristic which designates a determinate period of said day. 75

6. A transfer-ticket for issuance to or from public conveyances, comprising a slip which bears upon its face matter constituting it a valid medium for the transference 80 of passengers from one carline to another and in nonseparable relation to said matter, a distinctive symbol composed of one or more arbitrary characters, which signifies without other designation, a determinate 85 day of a determinate month, and which has a distinguishing color which designates a determinate period of said day.

In testimony whereof we have affixed our signatures in presence of two witnesses.
